L. J. LE PONTOIS,
IGNITION BREAKING DEVICE,
APPLICATION FILED JUNE 23, 1910.

1,149,843.

Patented Aug. 10, 1915.

UNITED STATES PATENT OFFICE.

LEON J. LE PONTOIS, OF CLEVELAND, OHIO, ASSIGNOR TO HURD & HAGGIN, A CORPORATION OF NEW YORK.

IGNITION-BREAKING DEVICE.

1,149,843.

Specification of Letters Patent. Patented Aug. 10, 1915.

Application filed June 23, 1910. Serial No. 568,573.

To all whom it may concern:

Be it known that I, LEON J. LE PONTOIS, a citizen of the Republic of France, residing at Cleveland, in the county of Cuyahoga and State of Ohio, have invented certain new and useful Improvements in Ignition-Breaking Devices, of which the following is a full, clear, and exact specification.

This invention relates to an improvement 10 in breaking devices particularly adapted to such devices applied to electric ignition systems for explosive engines.

My object in general is to provide an improved breaking device which will act to 15 effectively break the circuit so as to secure improved ignition in the engine, irrespective of the speed controlling the interruption of the breaker.

Where mechanical interrupters are used, 20 such as in conjunction with magneto generators, it is sometimes difficult to obtain effective ignition in starting. This is due in a considerable degree to the slow speed at which the mechanical interrupters here- 25 tofore used are actuated, the speed of the mechanical interrupter being dependent upon the speed of the engine in starting.

By my invention I provide electric means which coöperates with the mechanical interrupting device to secure a rapid interruption of the circuit at the breaker, irrespective of the speed. This I accomplish by causing the current to create a magnetic field which acts to open the circuit of the 35 breaker quickly at slow speeds, the opening of the breaker by such means being much more rapid in action than is a mechanical interrupter at slow speeds when used by itself. Thus effective ignition for starting 40 the engine may be obtained by utilizing a magneto as a source of ignition energy, instead of being obliged to resort to a battery or other auxiliary ignition means for starting the engine. My invention is also ad- 45 vantageous at other than slow speeds owing to the fact that the magnetic force exerted due to my improvement coöperates with the mechanical interrupter, tending to give a more rapid interruption of the breaker and 50 improved ignition. Also the advantage is obtained of having less friction and consequently less wear upon the surfaces of the mechanical means for interruption.

These, and other objects and advantages 55 of my invention, will be understood from the

following description and accompanying drawings, in which—

Figure 1 is a side elevation of an inductor generator combined with a breaking device embodying my invention, the breaking device being shown in central vertical section; Fig. 2 is a front view of the breaking device shown in Fig. 1, detached from the inductor generator; Fig. 3 is a detail view on the line 3—3 of Fig. 2, and Fig. 4 is a diagram indicating the connections.

My invention may be applied to any of the well known forms of magneto generators, and it is therefore unnecessary to explain in detail the construction of such a device, but for the purposes of explanation and illustration I have shown in general in the accompanying drawings an inductor magneto generator which is shown and described in detail in my pending application Serial No. 547,218, filed March 4, 1910. In order to show the application of my present improvement to a magneto generator, such as described in my above mentioned pending application, I may state that this generator comprises in general a field element 1, having thereon a generating winding 5, shown in diagram in Fig. 3, enveloped by a second winding 6, the windings 5, 6 being connected by the conductor 16 to the breaker. The other terminal of the winding 6 is connected to a distributor arm 63, from which the current is distributed to the several contacts 70, 71, 72, 73, and led to the spark plugs of the engine indicated at 77. The remaining terminal of winding 5 is connected by the conductor 11 through the operator's switch 19 to ground. A condenser 20 is connected in shunt about the coil 5. A safety device for spark discharge is indicated at 29, 30, for protecting the windings from abnormally high electromotive forces or other abnormal conditions.

The rotatable inductor of the magneto is indicated at 7 and its shaft carries a cam 40 for mechanically actuating the breaker. A metal drum 41 incloses the parts of the breaking mechanism and is rotatably mounted upon one of the end frames of the inductor generator so as to be adjusted in position by means of the arms 42 for the purpose of adjusting the time of ignition as desired. The outer end of the drum 41 is inclosed by a cover 43 of insulating material. Fixed to a central partition of the

drum 41, but insulated therefrom is a metal bracket piece 44, this piece being held in position by an insulated bolt 45. The bracket 44 has an outwardly and downwardly extending part 46 which extends out through an opening in the cover 43. A screw 47 engages the part 46 and carries spring-pressed rings adapted to receive between them a conducting strip 48 which 5 serves to electrically connect the bracket piece 44 and the conductor 16 leading to the terminals of generating windings 5 and 6. The bracket 44 at one end carries a bolt 49 which is adjustable and secured in any position by the nuts shown. The lower end of 10 the bolt 49 carries a platinum contact 50 which forms the fixed contact of the breaker. The movable arm of the breaker 51 is pivotally supported on a stud 55 fixed to the drum 41, the arm 51 being insulated from 15 said stud 55 by the insulating bushing 56. I prefer to make the insulating bushing 56 of hard fiber, thereby gaining the additional advantage of a self-lubricating bearing. The spring 52 has one end pivotally secured to but insulated from the bracket 44, the other end being provided with a rounded head 57 for holding the arm 51 and sleeve 56 in position. This arrangement secures 20 the ready removal of the arm 51 from its support. The arm 51 is of soft iron and carries at its outer end the platinum contact 54 forming the movable contact of the breaker. The block 58 is fixed on the upper 25 side of said arm 51 to coöperate with the cam 40. A spring 53, shown as a coil spring, is insulated from the casing 41 and engages the movable end of the breaker arm 51 tending 30 to force the movable contact 54 of the breaker into engagement with the fixed contact 50.

Within the lower part of the casing 41 is located a magnet having a coil 80 surrounding a core 81. From the lower end of core 45 81 extensions 82 of soft iron extend upward, as indicated in Fig. 1, so as to complete a magnetic circuit from the core through the extensions and thence through the soft iron arm 51, or a portion thereof, to the core 50 81. It will thus be seen that when a current passes through the coil 80, a strong magnetic field will be created tending to attract the soft iron arm 51 and open the breaker against the pressure of spring 43. 55 The electrical circuit from the movable contact 54 and its arm is completed through the spring 52 through its lower end and thence by a connection to a terminal of coil 80, the other terminal of which is grounded, 60 the electrical connections being as indicated in the circuits in Fig. 3.

The operation of my improved apparatus will be understood from the following: As is usual in magneto generators the rotor 65 of the magneto is connected in such rela-

tionship to the moving parts of the engine as to secure approximately maximum current strength when the breaker acts to interrupt the primary circuit, the cam 40 also being in such angular position as to open 70 the breaker mechanically at approximately the same period of maximum current. The timing of the ignition is controllable manually or automatically by connections to either of the arms 42, 42, the movement of 75 which changes the time of ignition. When in operation the cam 40 serves to interrupt the primary circuit which may be traced in Fig. 4 from the ground connection at the right through operating switch 19, winding 80 5, conductor 16, through the breaker and coil 80 to ground. Such interruption causes a high electromotive force to be induced in the winding 6 causing the discharge at the spark plugs in the engine successively as 85 controlled by the distributor. The interruption of the primary or generating circuit in order to be effective should, as above explained, be very rapid, and it is obvious that at slow speeds, such as in starting the 90 engine, the breaking of the circuit by the mechanical interrupter will be comparatively slow. By the action of the electromagnet comprising the parts 80, 81 however, the passage of the current in the breaking 95 circuit as it reaches a maximum causes the electromagnet to create a strong magnetic field which serves to give a rapid break of the primary circuit independently of the action or speed of the mechanical means. 100 Thus at slow speeds a very rapid interruption of the primary circuit is obtained giving effective sparking in starting the engine. At high speeds the electromagnetic device also assists in giving a very rapid interruption of the primary circuit and reduces the friction and wear of the mechanical interrupting means. 105

Although I have described one form of my invention, it will be understood that the 110 same is capable of embodiment in various forms without departing from the scope of my invention.

Having thus described my invention, I declare that what I claim as new and desire 115 to secure by Letters Patent is,—

1. An ignition breaking device, comprising a rotary element, two contact elements, resilient means for securing electrical contact between said contact elements, mechanical means actuated by said rotary element for causing the separation of said contact elements directly, and electromagnetic means coöperating with said mechanical means for effecting the separation of said 120 contact elements.

2. An ignition breaking device, comprising a rotary device, a fixed contact element, a movable contact element, a pivoted arm carrying said movable contact element, a 125 130

cam adapted to be rotated by the shaft of said rotary device and arranged to move said pivoted arm, and an electromagnet connected in circuit with the ignition device for 5 moving said arm.

3. In an ignition breaking device, the combination with a generator, of a cam rotated by the shaft of said generator, a fixed contact element, a movable contact element, 10 a movable part carrying said movable contact element, said movable part being adapted to be moved by said cam, and an electromagnet in circuit with a winding of said generator and adapted to effect the separation 15 of said contacts.

4. In an ignition breaking device, the combination with a generator, of a breaking device comprising a cam rotated by the shaft of said generator, a fixed contact element, a 20 movable contact element, a movable part carrying said movable contact element, said movable part being adapted to be moved by said cam, an electromagnet connected in circuit with a winding of said generator and 25 adapted to effect the movement of said pivoted arm, and resilient means for restoring electrical contact between said contact elements.

5. An ignition breaking device, comprising 30 mechanical means and electrical means each for directly controlling the opening of the breaker, and common means for mounting said mechanical means and said electrical means.

35 6. An ignition breaking device, comprising a fixed contact element, a movable contact element, resilient means for securing electrical contact between said contact elements, mechanical means and electrical 40 means each for directly effecting the separation of said contact elements, and common mounting means for said resilient means and said mechanical and said electrical means.

7. An ignition breaking device, comprising 45 mechanical means and electrical means each for directly controlling the opening of the breaker, and adjustable common means for mounting said mechanical means and said electrical means, whereby the time of ignition 50 may be varied.

8. An ignition breaking device, comprising 55 a fixed contact element, a movable contact element, resilient means for securing electrical contact between said contact elements, mechanical means and electrical means each for directly effecting the separation of said contact elements, and adjustable common mounting means for said resilient 60 means and said mechanical and said electrical means, whereby the time of ignition may be varied.

9. In an ignition device, a circuit interrupter, a cam for actuating said interrupter to close the circuit, and an electromagnet for 65 actuating said interrupter to open the circuit.

10. In an ignition device, a current distributor, a circuit interrupter in series with said distributor, a cam for actuating said 70 interrupter to close the circuit, and an electromagnet for actuating said interrupter to open the circuit.

11. In an ignition device, a unitary structure comprising a current distributor, a circuit interrupter in series with said distributor, a contact controlling armature, 75 mechanical means for actuating said interrupter through the movement of said armature to close the circuit and electrically controlled means for actuating said interrupter to open the circuit.

In testimony whereof I affix my signature, in presence of two witnesses.

LEON J. LE PONTOIS.
